[57] CLAIM

The ornamental design for a hoop roller, as shown and described.

DESCRIPTION

FIG. 1 is a rear perspective view of a hoop roller showing my new design;

FIG. 2 is a front elevational view thereof shown on an enlarged scale;

FIG. 3 is a rear elevational view thereof;

FIG. 4 is a right side elevational view thereof; the side opposite being a mirror image;

FIG. 5 is a bottom plan view thereof;

FIG. 6 is a top plan view of the handle member;

FIG. 7 is a rear perspective view of a modified embodiment of the design shown in FIGS. 1 through 6;

FIG. 8 is a front elevational view thereof shown on an enlarged scale;

FIG. 9 is a rear elevational view thereof;

FIG. 10 is a right side elevational view thereof, the side opposite being a mirror image;

FIG. 11 is a bottom plan view thereof; and,

FIG. 12 is a top plan view of the handle member.

Fig.1.**Fig. 3.****Fig. 5.****Fig. 6.****Fig. 4.****Fig. 2.**

Fig. 7.**Fig. 11.****Fig. 12.****Fig. 8.****Fig. 9.****Fig. 10.**
